(57) **CLAIM**

We claim the ornamental frame design, as shown and described.

DESCRIPTION

FIG. 1 is a front perspective view of the frame design of the present invention showing our new design;

FIG. 2 is a top view thereof;

FIG. 3 is a rear view thereof;

FIG. 4 is a right side view thereof, the left side being a mirror image;

FIG. 5 is a frontal view thereof; and

FIG. 6 is a bottom view thereof.

FIG. 7 is a top view of a second embodiment of the frame design of the present invention;

FIG. 8 is a rear view of the second embodiment shown in FIG. 7;

FIG. 9 is a right side view of the second embodiment shown in FIG. 7, the left side being a mirror image;

FIG. 10 is a frontal view of the second embodiment shown in FIG. 7; and,

FIG. 11 is a bottom view of the second embodiment shown in FIG. 7.

The broken lines showing the wheels, foot board, handle brake and handle bars are for illustrative purposes only and do not form part of the claimed design.
